US00D779484S

(12) **United States Design Patent** (10) **Patent No.:** **US D779,484 S**
(45) **Date of Patent:** ** *Feb. 21, 2017

(54) **ELECTRONIC DEVICE**

(71) Applicant: **Apple Inc.**, Cupertino, CA (US)

(72) Inventors: **Jody Akana**, San Francisco, CA (US); **Bartley K. Andre**, Palo Alto, CA (US); **Jeremy Bataillou**, San Francisco, CA (US); **Daniel J. Coster**, San Francisco, CA (US); **Daniele De Iuliis**, San Francisco, CA (US); **M. Evans Hankey**, San Francisco, CA (US); **Julian Hoenig**, San Francisco, CA (US); **Richard P. Howarth**, San Francisco, CA (US); **Jonathan P. Ive**, San Francisco, CA (US); **Duncan Robert Kerr**, San Francisco, CA (US); **Shin Nishibori**, Kailua, HI (US); **Matthew Dean Rohrbach**, San Francisco, CA (US); **Peter Russell-Clarke**, San Francisco, CA (US); **Christopher J. Stringer**, Woodside, CA (US); **Eugene Antony Whang**, San Francisco, CA (US); **Rico Zörkendorfer**, San Francisco, CA (US)

(73) Assignee: **Apple Inc.**, Cupertino, CA (US)

(*) Notice: This patent is subject to a terminal disclaimer.

(**) Term: **15 Years**

(21) Appl. No.: **29/554,587**

(22) Filed: **Feb. 12, 2016**

Related U.S. Application Data

(63) Continuation of application No. 29/457,962, filed on Jun. 14, 2013, now Pat. No. Des. 749,563, which is a continuation of application No. 29/431,553, filed on Sep. 7, 2012, now Pat. No. Des. 684,571.

(57) **CLAIM**

The ornamental design for an electronic device, as shown and described.

DESCRIPTION

FIG. 1 is a bottom front perspective view of an electronic device showing the claimed design;

FIG. 2 is a bottom rear perspective view thereof;

FIG. 3 is a top front perspective view thereof;

FIG. 4 is a top rear perspective view thereof;

FIG. 5 is a front view thereof;

FIG. 6 is a rear view thereof;

FIG. 7 is a top view thereof;

FIG. 8 is a bottom view thereof;

FIG. 9 is a left side view thereof; and,

FIG. 10 is a right side view thereof.

The oblique shade lines in the figures show transparency or translucency.

The broken lines in the figures show portions of the electronic device that form no part of the claimed design.

FIGS. 1-10 are illustrated to show contrasting appearance. Areas of the electronic device that appear in different shades of gray represent areas with contrasting appearances.
